UNITED STATES PATENT OFFICE.

EDWARD F. GRANDY, OF EVERETT, MASSACHUSETTS.

HAND TACK-DRIVING MACHINE.

SPECIFICATION forming part of Letters Patent No. 609,426, dated August 23, 1898.

Application filed March 30, 1896. Renewed January 22, 1898. Serial No. 667,861. (No model.)

To all whom it may concern:

Be it known that I, EDWARD F. GRANDY, a citizen of the United States, residing at Everett, in the county of Middlesex and State 5 of Massachusetts, have invented certain new and useful Improvements in Hand Tack-Driving Machines; and I do hereby declare the following to be a full, clear, and exact description of the invention, such as will enable 10 those skilled in the art to which it appertains to make and use the same.

This invention relates to improvements in hand-operated tack-driving machines which materially assist in their manipulation.

15 This invention is shown in combination with the tack-driving machine patented June 27, 1893, by Crisp and Junkins and numbered 500,225, to which reference is hereby made.

In the drawings, Figure 1 is a side elevation 20 of a tack-driving machine, showing the driving-hammer mounted thereon in operative position. Fig. 2 is the same side elevation, partly in section, showing the manner of connecting the hammer to the plunger of the tack- 25 driving machine.

This improved machine is constructed as follows:

The shell A of the machine hereinbefore referred to is fitted to receive an outer shell 30 1, adapted to be grasped by the hand of the operator. The upper end of the plunger B is also fitted to the interior of the shell 1, where it is secured to the shell 1 by the cap-screw 2, as shown in Fig. 2 of the drawings.

35 The raising-spring B² may be dispensed with, if desired, as the weight of the parts connected to the shell A is sufficient to cause said shell to assume the position shown by the drawings, when the shell 1 is grasped by the

hand of the operator and the machine held 40 vertically, in which position the machine is ready to drive a tack, which I consider an equivalent construction.

The operation of this machine is as follows: 45 With the machine held in the hand of the operator by the sleeve 1 the operator places the tack-delivery nozzle F upon the work at the place it is desired to drive a tack and by a downward motion of the hand on the sleeve 1 drives the tack. The weight of the sleeve 1 50 acting upon the plunger B as a hammer and the velocity given it by the operator governs at will the depth the tack is driven. The act of removing the machine from the work causes the parts to assume their normal position ready to drive another tack. 55

The advantages of the above-described invention are that it leaves one hand of the operator free for any desired manipulation, and at the same time does not materially increase the weight of the machine, and yet increases the facility with which it can be 60 grasped and operated.

Having thus described my invention, what I claim, and desire to secure by Letters Patent of the United States, is—

In a hand tack-driving machine, a sleeve 70 mounted to reciprocate over the part of the machine usually grasped by the hand of the operator, and rigidly fixed to the hollow driving-plunger, in combination with said plunger having a spring inclosed therein and a rigid nose, substantially as set forth.

EDWARD F. GRANDY.
